UNITED STATES PATENT OFFICE.

GEORGE A. WILLIAMS, OF WATERTOWN, CONNECTICUT.

METAL-CAN NOZZLE AND CLOSURE THEREFOR.

1,339,245.

Specification of Letters Patent. Patented May 4, 1920.

Application filed March 20, 1916. Serial No. 85,235.

To all whom it may concern:

Be it known that I, GEORGE A. WILLIAMS, a citizen of the United States, residing at Watertown, in the county of Litchfield and State of Connecticut, have invented a certain new and useful Improvement in Metal-Can Nozzles and Closures Therefor, of which the following is a full, clear, and exact description, reference being had to the accompanying drawings.

This invention relates generally to metal cans and more particularly to a nozzle and closure for the same.

Heretofore metal cans have been provided with comparatively short nozzles and consequently great difficulty has been experienced in pouring the liquid from the can through the said nozzle, and in some instances supplemental devices have been attached to the nozzle proper to facilitate the pouring operation.

Various forms of nozzle closures have also been employed in connection with the aforesaid short nozzle, but all such closures require the use of a machine or tool in applying the same, and after the closure has once been removed it is impossible to replace the same upon the nozzle and properly reseal it.

One of the objects of my invention, therefore, is to provide an elongated nozzle which will greatly facilitate the pouring of the liquid from the can, such nozzle being of such construction as to prevent bubbling or foaming at the mouth of the nozzle; and another object of the invention is to provide a nozzle and closure therefor of such construction that if desired said closure can be applied by hand and a perfectly tight seal obtained; and furthermore this closure is of such nature, and co-operates with the nozzle in such a manner, that it can be easily removed and replaced, and the opening and closing operations repeated as often as desired without impairing the tightness of the seal.

Another object of the invention is to provide a nozzle and closure of such construction that the closure can, if desired, be applied by machine or tool.

With these various objects in view the invention consists in the novel features of construction hereinafter fully described and pointed out in the claims.

In the drawings forming a part of this specification Figure 1 is a perspective view showing the upper portion of a can provided with my novel construction of nozzle and closure; Fig. 2 is a side elevation of the upper portion of the can, the closure being removed from the nozzle; Fig. 3 is a detail perspective view illustrating the nozzle with the closure removed; Fig. 4 is a detail sectional view showing the nozzle with the closure sealed thereon; Fig. 5 is a sectional view on the line 5—5 of Fig. 4 looking in the direction of the arrow; Figs. 6 and 7 are views illustrating the manner of sealing the closure upon the nozzle, and Figs. 8, 9, 10 and 11 are modified forms of nozzle.

Referring to the drawings A, indicates the metal can, B, the nozzle and C, the closure therefor. The metal can may be of any style or shape and of any desired size. The nozzle is of considerable length as compared with nozzles heretofore employed and may be described as elongated; this nozzle being secured in the head of the can in the usual manner, and at its extreme outer end it is rolled over, preferably inwardly and downwardly as indicated at 10, thereby somewhat contracting the discharge mouth. Directly below the outer or upper end of the nozzle, the sides are made inclined or tapering as shown at 11, and are then swelled outwardly as shown at 12, and at the end of said swelled portion 12, is produced an annular exterior shoulder 13. The end of nozzle may be rolled over outwardly and downwardly as shown in Figs. 10 and 11 providing a rounded but an unobstructed mouth. From the shoulder 13 to the head of the can the nozzle is very slightly tapered so as to allow the drawing punch to be withdrawn.

It will be noted, therefore, that looking at the nozzle from the interior there is a slight contraction just above the annular shoulder

13 and then there is an expansion providing the annular space 14, and then the further contraction due to the rolling in of the extreme end of the nozzle.

5 In pouring liquid from the can the unusual length of the nozzle has been found highly beneficial, and the formation of the nozzle upon the interior above the annular shoulder 13 permits pouring the contents in 10 a steady unbroken manner, due to the fact that the liquid is first contracted slightly and then permitted to expand into the annular space 14 and then be discharged through the inwardly contracted and rounded mouth which has the effect of completely 15 eliminating the bubbling and frothing, common with the short wide nozzles in common use.

For the purpose of tightly closing and 20 sealing the nozzle I employ a cap C consisting of a slotted apron to which is connected a contracting ring 20, and to the ends of this ring is connected the lever 21 which is so constructed as to contract the ring 25 when said lever is thrown down to its locked position, thereby securely binding the cap upon the end of the nozzle, and the inclined portion 11 of the nozzle facilitates this binding action as the contracting ring is drawn 30 down upon the inclined or tapered portion as it is contracted by the lever, and as the cap has a suitable sealing liner or filler 22, it will contact with the rounded mouth of the nozzle and effect a perfectly tight seal.

35 The exterior annular shoulder 13 serves as a fulcrum for the lever 21 during the clamping operation, and furthermore this annular shoulder also serves as the means for engaging the support 23 which constitutes a part of the machine or tool used during the sealing operation, said support being shown in dotted lines in Fig. 6 resting directly beneath the annular shoulder 13 thereby relieving the head of the can of pressure 45 during the sealing operation, it being understood that any suitable means may be employed for throwing the lever down, and in Figs. 6 and 7 I have shown in dotted lines a rotating finger capable of accomplishing the proper movement of the lever, said rotating finger being operated by any suitable mechanism.

It will thus be seen that the annular shoulder 13 performs the double function of serving 55 as a fulcrum for the clamping lever and also as a means for supporting the nozzle and relieving the head of the can from pressure during the sealing operation.

While I have shown one particular type 60 of cap and fastening means to be used as a closure in connection with the novel form of nozzle, it is obvious that other forms of closures may be employed, provided they have a contractible and expandible skirt,

together with means for contracting and fastening the same upon the end of the nozzle.

Having thus described my invention, what I claim is:—

1. In a metal can, a nozzle having its extreme outer end rolled inwardly and downwardly and spaced from the sides of said nozzle, said nozzle also having an exterior annular shoulder adjacent the upper end thereof. 70

2. A metal can having an elongated nozzle the extreme outer end of which is rolled inwardly and downwardly and spaced from the sides thereof, an exterior annular shoulder adjacent the outer end of said nozzle, 80 the sides of said nozzle below the inwardly rolled end and above the exterior shoulder being tapered inwardly and downwardly.

3. A metal can having an elongated nozzle, the extreme outer end being rolled inwardly and downwardly, said nozzle having an exterior annular shoulder adjacent the outer end thereof, the sides of the nozzle between the inwardly rolled end and the shoulder being inclined first inwardly and 90 then outwardly.

4. In a metal can, the combination with a nozzle, the length of which is in excess of its diameter, the discharge end of said nozzle being rounded inwardly and downwardly and spaced from the sides thereof, said nozzle having an exterior annular shoulder adjacent its outer end, of a detachable, expandible and contractible closure 95 adapted to be fitted upon the outer end of said nozzle and secured by contracting said closure upon the same. 100

5. A nozzle for containers, made of a single piece of sheet metal formed with a pouring opening and below said opening 105 with an outward projection adapted to support said nozzle against sealing pressure, and formed with an inwardly bent circular portion between said opening and said projection; whereby a gasket may be tightly seated with pressure by the aid of said projection and said pressure maintained by the aid of said inwardly bent portion. 110

6. A nozzle for containers, made of a single seamless piece of sheet metal formed 115 with a beaded lip and with an outwardly bent bead constituted of two thicknesses of metal flattened together, and formed with an inwardly bent circular portion between said lip and said flattened bead; whereby 120 a gasket may be tightly seated with pressure by the aid of said bead and said pressure maintained by the aid of said inwardly bent portion.

7. A sheet metal nozzle for containers, 125 having a pouring opening and formed with an outward projection below said opening adapted to support the nozzle while it is

being sealed, and formed with an inwardly bent circular portion between said opening and said projection, a gasket on the top end of the nozzle and indented thereby, a cap 5 inclosing said gasket and having depending flange portions inclosing the upper part of the nozzle and engageable in said inwardly bent portion, and means for contracting said flange portions into said inwardly bent portion; whereby the gasket may be tightly 10

seated with pressure by the aid of said bead and said pressure maintained.

In testimony whereof, I hereunto affix my signature in the presence of two witnesses.

GEORGE A. WILLIAMS.
